(57) **CLAIM**

The ornamental design for a vehicle front grille portion, as shown and described.

DESCRIPTION

FIG. 1 is a front view of a vehicle front grille portion according to the present invention.

FIG. 2 is an enlarged front view of the front grille portion shown in FIG. 1.

FIG. 3 is a front left perspective view of the front grille portion shown in FIG. 1; and,

FIG. 4 is an enlarged front left perspective view of the vehicle front grille portion shown in FIG. 3.

In the Figures any elements shown outside the broken line form no part of the claimed design, but are instead included to show environmental aspects thereof. The broken line forms a boundary of the claimed design.

1 Claim, 4 Drawing Sheets
